GAUGE

John A. Croston, Parkland, Wash.

Application March 2, 1942, Serial No. 433,076

2 Claims.

(Cl. 33—172)

The present invention relates to new and useful improvements in gauges or indicators for use particularly in lathes, boring machines, planers, etc., and has for its primary object to provide, in a manner as hereinafter set forth, an instrument of this character comprising a novel construction, combination and arrangement of parts whereby the device may be expeditiously adjusted to meet various conditions that may be encountered.

Another very important object of the invention is to provide a gauge of the aforementioned character with which various makes of conventional dial indicators may be used.

Other objects of the invention are to provide a gauge or dial indicating device of the character described which will be comparatively simple in construction, strong, durable, highly efficient and reliable in use, compact and which may be manufactured at low cost.

All of the foregoing and still further objects and advantages will become apparent from a study of the following specification, taken in connection with the accompanying drawings wherein like characters of reference designate corresponding parts throughout the several views, and wherein:

Figure 1 is a view in side elevation of a gauge constructed in accordance with the present invention.

Figure 2 is a view in horizontal section, taken substantially on the line 2—2 of Figure 1.

Figure 3 is a cross-sectional view, taken substantially on the line 3—3 of Figure 2.

Figure 4 is a view in front elevation of the instrument.

Figure 5 is a detail view in side elevation of the contact finger.

Figure 6 is a view in end elevation of the male member of the longitudinally extensible plunger.

Figure 7 is a perspective view of the female member of the plunger.

Figure 8 is a perspective view of the male member of the plunger.

Figure 9 is a perspective view of the sleeve in which the plunger is mounted.

Figure 10 is a detail view in top plan of the resilient clamp in which the sleeve is mounted.

Referring now to the drawings in detail, it will be seen that the embodiment of the invention which has been illustrated comprises a bar 1 of suitable metal for mounting in the lathe or other machine, said bar being substantially rectangular in cross-section, as seen in Figure 3 of the drawings. Projecting from the forward

end of the bar 1 is an integral arm 2. At its free or forward end, the arm 2 terminates in an upwardly offset longitudinally projecting split tubular clamp 3.

5 Firmly secured on the bar 1 is a conventional dial indicator 4 comprising a pointer 5. The indicator 4 further includes a slidable pin or the like 6 which actuates the pointer 5. The pin 6 of the indicator 4 is aligned with the clamp 3.

10 Mounted for rotary and sliding adjustment in the clamp 3 is a sleeve 7. On the forward end of the sleeve 7 is a fork 8. Journaled on a pin 9 between the bifurcations of the fork 8 is a work-contacting finger 10 which terminates in a ball head 11 on its free end. Formed integrally with the pivoted end of the contact finger 10 is a pair of spaced cams 12, the purpose of which will be presently set forth.

20 Slidably mounted in the sleeve 7 is a longitudinally extensible plunger which is designated generally by reference numeral 14. The plunger 14 comprises telescopic male and female members 15 and 16, respectively. The female member 16 includes, on its forward end, a substantially flat head 17 which is slidable between the bifurcations of the fork 8, said head including oppositely inclined faces 18 with which the cams 12 are engaged for actuating the plunger 14 toward the indicator 4 when the finger 10 is swung in either direction on its pivot 9.

25 The male member 15 of the plunger 14 comprises a longitudinally split, expanded inner end portion 19 which frictionally secures said male member in adjusted position in the female member 16. The other end portion of the male member 15 is tapered, as at 20, and is engageable with the pin 6 for actuating the indicator 4.

30 It is thought that the operation of the device will be readily apparent from a consideration of the foregoing. Briefly, as the finger 10 engages the work and is caused to swing on its pivot 9 thereby, one of the cams 12, according to the direction in which the finger is swung, engages the adjacent face 18 of the head 17 for moving the plunger 14 toward the indicator 4 thus actuating said indicator. The rotary mounting of the sleeve 7 in the split resilient clamp 3 permits the finger 10 to be swung to any desired position. To extend the instrument, the sleeve 7 is moved forwardly in the resilient clamp 3 until the finger 10 is in the desired position. The telescopic plunger 14 is then extended to engage the male member 15 with the pin 6 of the indicator 4 and the head 17 of the female member 16 is engaged 35 with the cams 12. The device is now ready for

operation, the adjustment of the male and female members 15 and 16, respectively, of the plunger 14 being frictionally maintained by the expanded end portion 19 of said male member. Of course, the split clamp 3 frictionally secures the sleeve 7 in adjusted position. The construction and arrangement is such that the instrument may be expeditiously assembled or disassembled.

It is believed that the many advantages of a gauge or indicating device constructed in accordance with the present invention will be readily understood and although a preferred embodiment of the instrument is as illustrated and described, it is to be understood that changes in the details of construction and in the combination and arrangement of parts may be resorted to which will fall within the scope of the invention as claimed.

What is claimed is:

1. A gauge of the character described comprising a bar, an indicator mounted on said bar, a longitudinally split, resilient tubular clamp on the bar, a sleeve rotatably and slidably mounted in the clamp and frictionally secured in adjusted

position therein, a plunger slidable in said sleeve and operatively connected to the indicator, and a work-actuated contact finger pivotally mounted on the sleeve and operatively connected to said plunger, the plunger including telescopically adjustable male and female members, said male member comprising a longitudinally split, expanded inner end portion for frictionally securing said members against relative longitudinal movement.

2. A gauge of the character described comprising a bar, an indicator mounted on said bar, a sleeve mounted on the bar, a plunger slidable in said sleeve and operatively connected to the indicator, said plunger including telescopically adjustable male and female members, said male member comprising a longitudinally split, expanded inner end portion for frictionally securing the members in adjusted position, and a work-actuated contact finger pivotally mounted on the sleeve and operatively connected to the plunger.

JOHN A. CROSTON.
